GYROSCOPIC POSITION FINDER

Fletcher M. Young, Berkeley, Calif., assignor of
one-half to Michael C. Casserly, San Mateo,
Calif.

Original application November 7, 1931, Serial No.
573,641. Divided and this application Septem-
ber 27, 1932, Serial No. 635,065

9 Claims. (Cl. 33—204)

My invention relates generally to position finders and more particularly to gyroscopic devices to be used in such installations for automatically indicating geographic positions in terms of longitude. The apparatus of the present invention is adapted to be used in connection with any known means of conveyance, and is applicable alike to vessels at sea, to land vehicles, or to air craft.

Heretofore it has been proposed to employ gyroscopic means for indicating longitude and latitude, but such proposals were based on the erroneous presumption that a gyroscope, when once set in motion, will necessarily maintain its spinning axis fixed in space.

While it is true that the spinning axis tends to remain fixed in space, this condition persists only so long as there is no external force acting on the gyroscope. Any gyroscope within the influence of the earth's gravitation will be rotated with the earth, and the force of this rotation will have its effect on the direction of the spinning axis of the gyroscope and will cause the axis to precess under the influence of the applied force. Also, some frictional forces are necessarily present in any gyroscope system, and these forces will likewise disturb the direction of the spinning axis unless counteracted or compensated for. When the gyroscope is mounted on a moving body, such as a ship, numerous forces arising from the pitching and rolling of the ship, its change in course and its change in speed, all have their effect on the spinning axis of the gyroscope. Even the force resulting from the movement of the earth in its orbit may in time be felt by the gyroscope. Prior gyroscopic position finders have failed to counteract, to neutralize, or to eliminate any of these forces, and for this reason have been entirely inoperative to produce the results sought. The mere fact that the tedious methods of dead reckoning and of resorting to astronomical observations are still universally employed in finding positions, is conclusive that no automatic position finder has heretofore been devised which is accurate within practicable limits.

It is an object of my invention to provide an automatic gyroscopic position finder which is accurate and dependable, and which will afford a direct position indication which need not be translated by computation.

Another object is to provide means in a device of the character described for counteracting the effect of external forces.

Another object is to provide a gyroscopic position finder in which novel means is provided for

minimizing and counteracting the effect of frictional forces.

Still another object is to provide a gyroscopic position finder in which a horizon instrument is employed for providing a basic plane from which the coordinates of the position can be derived.

Still another object is to provide a longitude indicating gyroscope in which possible errors due to external forces are eliminated, neutralized or counteracted.

Another object is to provide a longitude indicating gyroscope in which the effect of the force of the earth's rotation is automatically neutralized.

These and other objects and advantages are obtained in the embodiment of my invention illustrated in the accompanying drawings, in which:

Figure 1 is a diagrammatic view illustrating the principles of operation of the longitude indicating apparatus.

Figure 2 is a plan view partly in section, of an apparatus incorporating the present invention, taken on line 2—2 of Fig. 3.

Figure 3 is a cross sectional view taken along the planes indicated by line 3—3 of Figure 2.

Figure 4 is a cross sectional view taken along the plane indicated by line 4—4 of Figure 3.

Figure 5 is a detail view, partly in section, showing the apparatus for rotating the gyroscope in retrograde about an axis parallel to the polar axis of the earth.

Figure 6 is a detail view of the control contacts for controlling the energization of a follow up motor and one of the retrograde motors shown in Figure 5.

Figure 7 is a circuit diagram.

Figures 8 to 10 are detail views of the longitude indicator repeater card.

Figure 11 is a detail view of a dial and an impulse transmitter actuated in accordance with the movements of the gyroscope, taken on line 11—11 of Fig. 3.

Figure 12 is a circuit diagram.

Figures 13 to 15 illustrate diagrammatically the general relationship of the component parts of the position finder.

The invention claimed herein relates particularly to mechanism incorporated in a complete position finder installation for indicating a position in terms of longitude. In this connection the present case is a division of my copending application Serial No. 573,641, filed November 7, 1931, and entitled "Gyroscopic position finder".

The complete position finder with which I prefer to employ my invention comprises a pair

of gyroscopes, one of which is employed for indicating longitude and the other for indicating latitude. Preferably, both of these gyroscopes are free and non-pendulous for minimizing friction and for counteracting any tendency of the spinning axes of the gyroscopes to change their respective directions in space under the influence of external forces.

The two gyroscopes referred to above are preferably utilized in conjunction with a third gyroscope which is made north-seeking and pendulous, so that its spinning axis continually takes a horizontal position or one tangent to the earth's surface and lying in the north and south plane. Gyroscopes of the last mentioned type are in common usage as compasses on ships and, if desired, the gyrocompass which is usually utilized on ships can serve as the third gyroscope. A suitable horizon instrument is also utilized to establish a horizon line or a plumb line from which the coordinates can be determined. As will be presently explained, such a horizon instrument can be connected to certain other parts of the apparatus by suitable means.

The directive force of the earth's rotation, which is employed to direct the spinning axis of the latitude gyroscope disclosed in said copending application, is counteracted in the longitude gyroscope by rotating the longitude gyroscope about an axis parallel to the earth's polar axis and at the same rate as the earth's rotation, but in the opposite direction. Thus, the precession which would otherwise be caused by the force of the earth's rotation, is neutralized by the force set up by the retrograde rotation given to the gyroscope, and the gyroscope remains in equilibrium between these two forces. So long as these forces remain exactly equal, therefore, there will be no tendency of the gyroscope axle to change its direction in space. If the gyroscope is mounted on a ship, and the ship moves in a direction which has an easterly or westerly component, the resultant rotation of the gyroscope due to the rotation of the earth and the movement of the ship over the surface of the earth is greater or less than one revolution in twenty-four hours, by an amount which is determined by the speed and the course of the ship. In order to maintain the gyroscope in equilibrium under these conditions the retrograde rotation imparted to the gyroscope must be increased or diminished accordingly, so that the retrograde rotation neutralizes exactly the resultant rotation of the gyroscope due to the earth's rotation and the movement of the ship. North and south movements of the ship will not affect the rate of rotation of the gyroscope about the axis of the earth and need not be taken into consideration.

The principles on which the longitude gyroscope operates are illustrated in Fig. 1. The gyroscope is preferably set in motion with its spinning axis lying in a plane parallel with the plane of the equator and with its disc parallel to the plane of a known meridian at a definite time, chosen as the origin, preferably the meridian at Greenwich at noon. As the earth rotates about its axis, the gyroscope is given a retrograde rotation about an axis parallel with the axis of rotation of the earth and at the same rate, but in the opposite direction. The retrograde rotation of the gyroscope is increased or diminished in accordance with the speed and direction of the ship's travel over the earth to maintain the disc of the gyroscope parallel with the noon position in space of the meridian at Greenwich. Thus,

the gyroscope remains relatively fixed in space. The longitude, of any position is determined by laying off the hour angle of Greenwich eastwardly from the zenith line of the gyroscope disc, thereby obtaining a line parallel to the plane of the meridian at Greenwich at that time. The longitude of the place is then given by the angle between the line thus obtained and the vertical plane through the meridian at the location of the instrument.

Referring now to the examples illustrated in Fig. 1, K illustrates the position of the gyroscope disc when the gyroscope is at 60° west longitude at noon Greenwich, the latitude being 0°. It will be noted that the axis of the gyroscope lies in a plane parallel with the plane of the equator and that the disc of the gyroscope is in a plane parallel with the noon position of the Greenwich meridian. The hour angle of Greenwich is zero, so no angle is laid off from the zenith line of the gyroscope disc, the gyroscope disc itself giving the parallel of the meridian at Greenwich at that time. Measuring the angle between the zenith line of the gyroscope disc and the earth's vertical, we obtain 60°, the longitude of the place.

Assuming now that the ship is traveling westward at the rate of one-half degree per hour, the position of the gyroscope K will be moved by the earth's rotation and by the motion of the ship to K' at 2:00 p. m. Greenwich time. During this motion in space of the gyroscope, it has been given a retrograde rotation equal to the resultant rotation about the earth's axis, so that its axle remains parallel to the plane of the equator and its disc remains parallel with the noon position in space of the Greenwich meridian. The hour angle r of Greenwich is 2/24ths of 360°, or 30°, and this angle is laid off in an eastward direction from the origin mark of the gyroscope case giving the line n which is parallel to the meridian at Greenwich at 2:00 p. m. The angle between the line n and the earth's vertical or plumb line is equal to 60° plus the ship's angular movement about the axis of the earth or 61°, indicating 61° west longitude. If the ship had been traveling eastward instead of westward, its angular movement would have been negative instead of positive and the angle between the line n and the plumb line in that case would have been 59°, and the longitude indication would have been 59° west longitude.

The position of the gyroscope at 30° east longitude at 2:00 p. m. is shown at K''. The hour angle r of Greenwich is laid off as before from the origin mark of the gyroscope case, giving the line n' parallel to the meridian at Greenwich at that time. The angle between the line n' and the plumb line under these conditions measures 30°, indicating 30° east longitude.

In general, therefore, the method of indicating the longitude comprises rotating the gyroscope to counteract the effect of the earth's rotation, laying off the hour angle of the meridian chosen as the origin in the direction of the earth's rotation to obtain a line parallel with the plane of the origin meridian at the time of observation, and then measuring the angle between the last mentioned line and the line in the vertical plane through the instantaneous meridian parallel to the plane of the equator.

Referring now to Figs. 2 to 15, I have shown a gyroscope supported for rotation in a plurality of gimbal rings and maintained with its axis of rotation in the plane of the equator and with its

disc parallel to a chosen meridian plane at a definite time. The origin meridian is preferably the meridian at Greenwich and the disc of the gyroscope lies in a plane parallel to the plane of this meridian at noon Greenwich. As the earth rotates and as the ship moves in longitude over the surface of the earth, the gyroscope is turned accordingly to maintain its disc parallel with the noon position of the Greenwich meridian.

10 For supporting the gyroscope a binnacle 302 is provided which is mounted in any suitable manner on the ship. A floating ring 303 is suspended in springs 304 from the binnacle 302. A ring 306 is carried in fore and aft trunnions 307 and 308 in ring 303. A leveling motor 309 is provided for leveling the ring 306 athwartship and is controlled by a suitable horizon instrument. A ring 311 is carried in athwartship trunnions in ring 306 and is kept in a vertical plane by motor 312 (Fig. 4), 15 similar in operation to the motor described in connection with the latitude instrument of the aforesaid co-pending application. Carried in vertical trunnions 313 and 314 in ring 311 is a ring 316 and a motor 317 (Fig. 3), operating in a manner 20 similar to the motor 71 of the aforesaid latitude instrument, is provided for maintaining the ring 316 in a plane parallel to the E-W vertical plane. Carried in east and west trunnions in ring 316 is a ring 318. Ring 318 is kept in a plane parallel 25 with the plane of the Equator by a motor 319 mounted on ring 316 and carrying a pinion 321 which meshes with a gear 322 on ring 318. The motor 319 receives impulses from a latitude repeater transmitter to maintain the ring 318 parallel with the plane of the Equator.

30 Rigidly secured to ring 318 and extending at right angles thereto to lie in the north and south vertical plane is a ring 323. Ring 323 carries a ring 324 which is mounted for rotation about 35 trunnions 326 and 327 which are in a N-S plane and normal to the Equator. Ring 324 carries the gyroscope housing 301 in trunnions 328 and 329 lying parallel to the plane of the Equator. Interposed between the gyroscope housing 301 and the ring 324 is a follow-up ring 331 which is caused to follow the movements of the gyroscope 40 about trunnions 328 and 329.

45 For causing the ring 331 to follow the movements of the gyroscope, a motor 332 is provided which is mounted on ring 324 and which carries a pinion 333 meshing with a gear 334 rigidly secured to the ring 331. An arm 335 mounted on trunnion 328 to rotate therewith carries sets of contact wheels 337 and 338 (see Fig. 6) which cooperate 50 with follow-up contacts 339 and 341 carried by ring 331 to energize the motor 332 to bring the ring 331 back into the plane of the gyroscope disc, whenever there has been relative rotation between the ring 331 and the gyroscope disc to disturb 55 this relationship.

60 For rotating the gyroscope housing about the trunnions 326 and 327 in a direction opposite to the direction of the earth's rotation and at the same rate, I provide a motor 342 which is mounted on ring 323. Motor 342 carries a pinion 343 which meshes with a gear 344 secured to a shaft 346 which carries a worm 347. Worm 347 drives a worm gear 348 at the rate of one revolution in 65 24 hours and in a direction opposite to the direction of rotation of the earth. For transmitting the rotation of gear 348 to the gyroscope housing 301, gear 348 is fixed to a sleeve 349 which carries a worm gear 351 similar in every respect with the gear 348. Sleeve 349 is rotatable 70 relative to the trunnion 328 and relative to the

ring 323. A reduction gear train comprising the worm 352, gear 353 and pinion 354 connects the gear 351 with a motor 356 mounted on ring 324. Motor 342 and motor 356 are similar to each other, but motor 342 is energized continuously to rotate 5 at a constant speed in one direction while motor 356 is normally de-energized and is adapted to be energized to rotate in one direction or the other to modify the effect of rotation of motor 342. Assuming that the motor 356 is de-energized, the motion of gear 348 which rotates at a constant rate of one revolution in twenty-four hours is communicated to the ring 324, the gear train 352 to 354 acting under such condition as a rigid connection between gear 351 and the ring 15 324. Ring 324, therefore, rotates at the rate of one revolution in twenty-four hours in a direction opposite to the direction of rotation of the earth and carries with it the gyroscope housing 301. During this rotation of the gyroscope, the 20 spinning axle remains east-west.

25 Motor 356 is energized only when the ship is traveling in a course which has an easterly or westerly component and the duration of the energization and the direction of rotation of the motor 356 is such that the rotation of the gyroscope is modified in accordance with the motion of the ship over the surface of the earth. In other words, when the ship is traveling west, the resultant rate of rotation of the entire device 30 about the axis of the earth is less than one revolution in twenty-four hours, and the motor 356 is energized to turn the ring 324 in the same direction as the earth's rotation by an amount which is sufficient to eliminate the effect of the 35 ship's movement toward the west. In a like manner, if the ship is traveling eastward, the motor 356 is energized to speed up the rotation of the gyroscope in accordance with the motion of the ship about the axis of the earth. In effect, 40 the plane of the gyroscope remains fixed relative to absolute space while the gimbal rings are rotated relative to the gyroscope about the trunnions 326 and 327, to enable the gyroscope to maintain such fixed relation. When the ship is 45 stationary or when it moves due north or due south, the rate of rotation is exactly equal to the rate of the earth's rotation about its axis, but in the opposite direction. When the ship moves east or west, however, and thus increases or decreases the virtual rate of rotation of the instrument about the axis of the earth, the retrograde rotation of the gyroscope is modified to neutralize 50 the effect of the virtual rotation.

55 For accomplishing this object, automatic means is provided for energizing the motor 356 to modify the effect of motor 342. As long as the gyroscope is rotated at a rate which causes its plane to remain parallel with its original direction in space, the directive force of the earth's 60 rotation will not be felt by the gyroscope. If, however, the ship moves to the east or to the west, the rate of the rotation of the gyroscope about trunnions 326 and 327 must be increased or decreased accordingly, otherwise the plane of the 65 gyroscope disc will deviate from its original position in space and the directive force of the earth's rotation will be felt. As soon as the directive force is felt by the gyroscope, its axle will begin to precess, the amount and direction of precession being in accordance with the directive force arising from the ship's rotation about the axis of the earth. This precession will cause the gyroscope to turn about the trunnions 328 and 329 70 relative to the ring 324. In order to overcome 75

this precession, the gyroscope rotation about trunnions 326 and 327 must be modified by an amount sufficient to set up an equal and opposite precession. The amount of supplemental rotation about trunnions 326 and 327 and its direction are such that the gyroscope will be brought back into a plane parallel with its original plane when the precession is neutralized.

For energizing motor 356 a contact arm 361 is secured to rotate with trunnion 328. Contact arm 361 carries contact wheels 362 and 363 which cooperate with contacts 364 and 366 carried by ring 324. When the gyroscope precesses it turns in one direction or the other relative to the ring 324, thus indicating that the rate of rotation of the gyroscope has at that instant varied from the virtual rate of rotation of the ship about the axis of the earth. Contacts 364 and 365 cooperating with the contact arm 361 thereupon complete a circuit to motor 356 to cause it to move the gyroscope back into the plane of origin. In doing so, the rate of rotation of the gyroscope is modified to equal the combined effect of the ship's motion and the earth's motion relative to the axis 25 of the earth. The plane of the gyroscope disc is in this manner kept in a plane parallel with the plane in space of the meridian which was chosen as the origin.

The circuit diagram for operating the motors 332, 342 and 356 is shown in Fig. 7. Motor 342 is connected directly to a source of regulated current impulses to rotate the gyroscope housing in retrograde at the rate of one revolution in twenty-four hours. If the gyroscope shows precession relative to the ring 324, certain ones of the contacts 364 and 366 are bridged, the upper contacts 364 closing simultaneously with the lower contacts 366 and the lower contacts 364 closing simultaneously with the upper contacts 366.

Assuming the direction of precession is such that upper contacts 364 and lower contacts 366 are bridged, current will flow from one side of the source of current, through conductor 371, upper contacts 364, motor 356, conductor 372, lower contacts 366, through conductor 373 back to the other side of the source of current. The motor 356 will then modify the rotation imparted to the gyroscope by motor 342 to bring the plane of the gyroscope back into the plane of ring 324. If the direction of precession is in the opposite direction, lower contacts 364 and upper contacts 366 are closed, thereby energizing the motor 356 in the opposite direction to modify the rotation of the gyroscope housing so that the gyroscope disc is again brought into a plane parallel with its original position. Precession of the gyroscope also causes the contacts 339 and 341 to be closed to energize the motor 332 in the proper direction to cause ring 331 to follow the precession of the gyroscope. While it is not desired to permit the gyroscope to precess out of the plane of its origin and to remain out of that plane, such precession, when it occurs, is employed to indicate when the gyroscope has moved out of its original plane and thus affords an indication when the retrograde rotation of the gyroscope is not exactly equal to the virtual rate of rotation of the ship about the earth's axis.

Thus, in my longitude apparatus, the directive force of the earth's rotation is employed to indicate the relationship of the plane of the gyroscope disc at any instant relative to the original plane. If the plane of the gyroscope disc is parallel to the original plane, no precession will be caused by the directive force of the earth's rota-

tion, because the parallel relationship of the gyroscope disc indicates in itself that the directive force of the earth's rotation has been exactly neutralized by the directive force set up by the retrograde rotation of the gyroscope. If, on the other hand, the directive force of the earth's rotation is felt, it indicates that the retrograde rotation of the gyroscope is either too fast or too slow, on account of the movement of the ship in an easterly or westerly direction. The rate of retrograde rotation must then be increased or decreased in accordance with the movement of the ship in longitude in order to neutralize the directive force of the earth's rotation compounded with the travel of the ship. The amount by which the retrograde rotation of the gyroscope differs from the rate of the earth's rotation is, therefore, the measure of the ship's movement in longitude. An indication of the longitude can be obtained, therefore, by subtracting the rotation of the earth from the total retrograde movement of the gyroscope, thereby obtaining the movement in longitude from the original position of the gyroscope, and adding to the result the longitude in which the gyroscope was started.

For accomplishing this calculation automatically, an indicator card, such as that shown in Figs. 8, 9 and 10, can be employed. A relatively stationary housing 376 is provided and a motor 377 secured to the housing carries a pinion 378 which meshes with a gear 379. The rate of rotation of the motor 377 is such that the gear 379 rotates at a rate which is equal to the retrograde rotation of the gyroscope. The gear 379 is secured to a shaft 381 which rigidly carries a disc 382. Disc 382, therefore, is also rotated at a rate which equals the rate of the retrograde rotation of the gyroscope, preferably in the direction of the arrow shown on the disc. The rate of retrograde rotation of the gyroscope is exactly 360° in twenty-four hours when the ship is stationary, but varies from this rate when the ship moves in longitude. Mounted on gear 379 is a motor 383 which carries a pinion 384 meshing with a gear 386. Gear 386 is secured to a hub 387 which is mounted for rotation relative to the shaft 381. Also secured to hub 387 is a ring 388 which surrounds the disc 382. Ring 388 is adapted to rotate in the direction of the arrow marked thereon relative to the disc 382 at a rate of exactly 360° in twenty-four hours. Since the disc 382 moves counter-clockwise relative to the housing 376 at the same rate that the ring 388 moves clockwise relative to the disc 382, when the ship is stationary, the ring 388 will remain stationary relative to the housing 376 under this condition. When the ship moves in longitude, however, the rate of rotation of disc 382 is increased or decreased accordingly and the amount by which this rate differs from the rate of rotation of ring 388, will be indicated by the relative movement of ring 388 with respect to the housing 376. The ring 388 is graduated about its outer periphery from zero to 180° in each direction, as at 389, and these graduations cooperate with a zero mark 391 and a vernier scale 392 on the housing to indicate the angular relationship of ring 388 with respect to the housing. A second zero mark 394 cooperates with the graduations 389 to indicate the supplement of the angle indicated at the zero mark 391. The zero mark 391 is used in making west longitude readings and the zero mark 393 is used in making east longitude readings.

The inner periphery of ring 388 is graduated from zero to 360°, as at 394, and a zero mark 395.

on disc 382 cooperates with this scale of graduations to indicate the angular displacement between disc 382 and ring 388. In initiating the apparatus, the zero mark 396 is made to indicate the hour angle of Greenwich, that is, so that the mark 396 will be opposite the zero mark on the scale 394 when it is noon Greenwich and so that thereafter it will indicate the time at Greenwich in terms of angular displacement 360° being made equivalent to twenty-four hours. The ring 388 is moved to indicate the known longitude of the place in which the apparatus is started. Thereafter, the disc 382 will rotate counter-clockwise at the rate of 360° in twenty-four hours, relative to the zero mark on the scale 394, thereby measuring the time at Greenwich in terms of angular displacement. As long as the ship does not move in longitude, the ring 388 will move clockwise relative to the disc 382 at the same rate that the disc 382 moves counterclockwise relative to the housing 376, the ring 388, therefore, remaining stationary relative to the housing 376 and constantly indicating the unvarying longitude.

Now, if the ship moves east or west and therefore in longitude, the retrograde rotation of the gyroscope must be modified accordingly to maintain the gyroscope disc parallel to the plane of its original position. The ring 388 will be moved under this condition relative to the housing 376 and the new longitude to which the ship has moved will be indicated by the scale 388.

The position of the dials in Fig. 8 indicates that the ship is at 30° west longitude at 6:00 p. m. Greenwich time. The zero mark 396 represents the position of the meridian at Greenwich at noon, and the angular displacement of the zero mark 396 from the zero point on the scale 394 is equal to the angular displacement of the meridian at Greenwich at 6:00 p. m. relative to its noon position. Comparing the readings shown in Fig. 8 with the notations employed in Fig. 1 for the position K', the zero mark 396 represents the zenith line of the gyroscope disc, the zero mark on the scales 389 and 394 represent the line n, and the zero mark 391 represents the vertical or plumb line of the earth.

For transmitting the retrograde rotation of the gyroscope to the disc 382, I have shown a gear 401 (Figs. 3 and 11) secured to the ring 324 to rotate therewith relative to the ring 323 about the trunnion 321. Meshing with the gear 401 is a pinion 402 and secured to the shaft 403 of the pinion are a pair of contact arms 404 and 406. Contact arms 404 and 406 sweep over a plurality of segments 407 (Fig. 11), thereby setting up a sequence of electrical impulses which are transmitted to the motor 377. Motor 377 is therefore energized in accordance with the angular displacement between rings 323 and 324, which is the measure of the retrograde rotation of the gyroscope. The gear ratio of the train between motor 377 and disc 382 is such that the disc 382 rotates relative to the housing 376 at exactly the same rate as the gyroscope is rotated in retrograde.

For energizing motor 383 a similar repeater circuit is provided, but slip ring connections are employed since the motor 383 is carried by the gear 378 and thus rotates relative to the housing 376. The impulses for energizing motor 383 are obtained from the transmitter actuated by the ship's chronometer or any other accurate time measuring device in such a manner that the frequency of the impulses is exactly sufficient to

rotate the ring 388 relative to the disc 382 at the rate of 360° in twenty-four hours. Thus, I have shown a transmitter having contact arms 404' and 406' carried by a shaft 403' which is rotated by a clock to set up a sequence of accurately regulated electrical impulses as the arms 404' and 406' sweep over the segments 407'. The impulses thus obtained are transmitted to a set of four slip rings 408 (Fig. 9), mounted on the housing 376 and insulated electrically from one another. A set of four contact wheels 409 each making electrical contact with one of the rings 408 complete the path for the electrical impulses through conductors 410 connected to the field windings of motor 383. In this manner the motor 383 is energized to rotate the disc 382 relative to the ring 388 at a rate of exactly 15° per hour at all times.

Preferably, an indicating arm 411 (Fig. 11) is secured to the ring 323 which cooperates with a graduated scale 412 on or carried by the gear 401 to indicate the angular displacement of the gyroscope from a fixed direction. This scale can be employed for initially placing the disc of the gyroscope in the desired starting position.

In explanation of the interrelation of my latitude and longitude gyroscopes it may be further explained that the retrograde rotation of the longitude gyroscope is for the purpose of eliminating the effect of the earth's daily rotation upon the gyroscope. The retrograde rotation must therefore be in a plane parallel to the plane of the earth's rotation, that is, the plane of the equator which is the same thing. The axis of the retrograde rotation must be at all times parallel to the earth's polar axis. To fulfill this requirement the north and south axis of the longitude gyroscope, about which the retrograde motor turns the instrument, is kept elevated to the angle of the latitude by repeater controls from the latitude instrument, or in other words the north and south axis of the longitude instrument is kept parallel to the axle of the latitude gyroscope, except when the direction of that axle requires correction due to the north-steaming error, at which time the automatic correction for the angle of latitude affects the longitude instrument as well as the latitude instrument. The north and south axis of the longitude instrument, being thus controlled from the latitude instrument, is therefore parallel to the earth's polar axis; for in its function of indicating latitude the axle of the latitude gyroscope is parallel to the earth's polar axis, the angle between the axle and the earth's north and south horizontal being equal to the latitude of the place. It is thus seen that the latitude instrument will function properly without aid or control from the longitude instrument, but that the longitude instrument is dependent upon the latitude instrument for proper functioning, since if the requirement stated in the preceding paragraph is not fulfilled, the longitude instrument will not indicate the correct angles of longitude. The only means at hand for so controlling the direction of the north-south axis of the longitude instrument lies in the use of the latitude instrument.

The general layout of the component parts of a complete installation incorporating my invention is illustrated in Figs. 13 to 15. Any desired number of repeater instruments 413 can be placed at convenient points on the ship, while the gyroscopic instruments can be placed in the position which is most satisfactory for their operation, in accordance with the present day practice in connection with gyrocompass installations.

The compass which is employed in my position finder may be the ship's gyrocompass or may be a gyrocompass designed especially for use with my invention.

5 It is to be understood that certain expedients now in common practice for improving the operation of gyrocompass installations can be incorporated in my gyroscopic position finder, wherever such expedients are applicable.

10 While I have shown and described a preferred embodiment of my invention, it is to be understood that I do not wish to be limited thereto, since the invention as defined in the appended claims can be embodied in other forms.

15 I claim:

1. In a gyroscopic device for indicating geographic positions, a gyroscope adapted to be set in operation with its spin axis parallel to the plane of the equator, and means for insuring 20 stable retrograde rotation of said gyroscope about an axis parallel to the polar axis of the earth in a direction opposite to the direction of the earth's rotation and at a rate which is sufficient to maintain the disc of the gyroscope parallel to the 25 plane of its original position, said means including motive means responsive to precessional movements of the gyroscope about an axis normal to the two above-mentioned axes.

2. In a gyroscopic device for indicating geographic positions in terms of longitude, a gyroscope having its disc parallel to the noon position 30 of the meridian of Greenwich, and adapted to be set into operation with its spin axis parallel to the plane of the equator, means for effecting 35 retrograde rotation of said gyroscope about an axis parallel to the polar axis of the earth in a direction opposite to the direction of the earth's rotation and at a rate which is sufficient to maintain the disc of the gyroscope parallel to the 40 plane of the noon position of the meridian of Greenwich, means for automatically laying off the hour angle of the meridian of Greenwich from the zenith line of the gyroscope disc, and means for automatically indicating the angle between the line thus obtained and the earth's 45 plumb line through the gyroscope.

3. In a gyroscopic device for indicating geographic positions, a gyroscope adapted to be set in operation with its spin axis parallel to the 50 equator, a supporting structure for said gyroscope, means interposed between said supporting structure and said gyroscope serving to carry the gyroscope for three degrees of freedom relative to the support, said last means including a gimbal 55 ring capable of having three degrees of freedom with respect to the supporting structure and with respect to which the gyroscope may have like freedom of movement, said ring being adapted to be maintained in a predetermined angular positioning with respect to the plane of the equator and the earth's north and south axis, and continuously operating driving means interposed between said gimbal ring and the gyroscope.

4. In a gyroscopic device for indicating geographic positions, a support adapted to be carried 65 by a ship or like moving structure, a gyroscope carried by the support and adapted to be set into operation with its spin axis parallel to the equator, means serving to interconnect the support with the gyroscope whereby the gyroscope is carried for three degrees of freedom, said last means including a gimbal ring capable of having three degrees of freedom with respect to the support and with respect to which ring the gyroscope is also capable of having like movement, means for 70

maintaining a gimbal axis of said ring parallel to the earth's north and south axis, said gimbal ring being also restrained against rotation about said axis, and driving means interposed between said gimbal ring and the gyroscope and serving 5 to insure relative rotation about said gimbal axis between said gimbal ring and the gyroscope at a rate sufficient to maintain the gyroscope in stable equilibrium with its spin axis parallel to the equator and irrespective of orientation of the device 10 in any direction.

5. In a gyroscopic device for indicating geographic positions, a support adapted to be carried by a ship or like moving structure, a gyroscope adapted to be set into operation with its spin axis parallel to the equator, means serving to interconnect the support with the gyroscope whereby the gyroscope is carried for three degrees of freedom, said last means including a gimbal ring capable of having three degrees of freedom with respect to the support and with respect to which ring the gyroscope is also capable of having like movement, means for maintaining a gimbal axis of said ring parallel to the earth's north and south axis, said gimbal ring being also restrained 25 against rotation about said axis, and driving means interposed between said gimbal ring and the gyroscope and serving to insure relative rotation about said gimbal axis between said gimbal ring and the gyroscope at a rate sufficient to 30 maintain the gyroscope in stable equilibrium with its spin axis parallel to the equator and irrespective of orientation of the device in any direction, said driving means including a motor adapted to effect a rate of relative rotation between said ring and said gyroscope equal to the rate of rotation of the earth and another motor serving to effectively increase or decrease said rate of drive in response to orientation of said device in easterly 35 or westerly directions.

6. In a gyroscopic device for indicating geographic positions, a support adapted to be carried by a ship or like moving structure, a gyroscope adapted to be set into operation with its spin axis parallel to the equator, means serving 45 to interconnect the support with the gyroscope whereby the gyroscope is carried for three degrees of freedom, said last means including a gimbal ring capable of having three degrees of freedom with respect to the support and with respect to which ring the gyroscope is also capable of having like movement, means for maintaining a gimbal axis of said ring parallel to the earth's north and south axis, said gimbal ring being also restrained against rotation about said axis, and driving means interposed between said gimbal ring and the gyroscope and serving to insure relative rotation about said gimbal axis between said gimbal ring and the gyroscope at a rate sufficient to 55 maintain the gyroscope in stable equilibrium with its spin axis parallel to the equator and irrespective of orientation of the device in any direction, said driving means being responsive to precessional movements of the gyroscope.

7. In a gyroscopic device for indicating geographic positions, a gyroscope adapted to be set into operation with its axis parallel to the equator, a support adapted to be carried by a ship or like moving object, means interconnecting said support with the gyroscope and serving to carry the 70 gyroscope for three degrees of freedom, said last means including a gimbal ring capable of having three degrees of freedom with respect to the support, and with respect to which the gyroscope is also capable of having like movement, said 75

5 gimbal ring being adapted to have gimbal axis of the same maintained parallel to the earth's north and south axis and being likewise restrained against rotation about said axis, driving means 10 interposed between said gimbal ring and the gyroscope and serving to insure relative rotation between said ring and said gyroscope at a rate equal to the rate of rotation but in an opposite direction, and means serving to modify said driving 15 rate in accordance with orientation of the ship in easterly or westerly directions, said last means including a follow-up mechanism operative responsive to precessional movements of the gyroscope, and motive means actuated in response to 20 the positioning of said follow-up mechanism.

8. In a gyroscopic device for indicating geographic positions in terms of longitude, a gyroscope adapted to be set into operation with its spin axis parallel to the plane of the equator, 25 means for effecting retrograde rotation of said gyroscope about an axis parallel to the polar axis of the earth and in a direction opposite to the earth's direction of rotation to maintain its an-

5 gular position fixed with respect to absolute space, a repeater card having a plurality of graduated dials, means interconnecting said dials for automatically moving one of them relative to the other in accordance with the rotation of the earth about its axis, a housing for said dials, and means controlled by retrograde rotation of the gyroscope for moving said dials and interconnecting means relative to said housing in accordance with the rate of said retrograde rotation. 10

9. In a gyroscopic apparatus for indicating geographic positions in terms of longitude, a gyroscope, said gyroscope when in operation having its spinning axis disposed parallel to the plane of the equator, means for supporting the gyroscope 15 for three degrees of freedom, motive means serving to apply forces to the gyroscope to substantially neutralize tendency toward precessional movements as the apparatus is moved in various directions over the earth's surface, and means 20 responsive to slight precessional movements of the gyroscope for controlling said motive means.

FLETCHER M. YOUNG.
